UNITED STATES PATENT OFFICE.

NELS EDWARD KNUTZEN, OF MANITOWOC, WISCONSIN.

TRACK-BRAKE.

SPECIFICATION forming part of Letters Patent No. 794,460, dated July 11, 1905.

Application filed October 31, 1904. Serial No. 230,850.

To all whom it may concern:

Be it known that I, NELS EDWARD KNUTZEN, a citizen of the United States, residing at Manitowoc, in the county of Manitowoc and State of Wisconsin, have invented certain new and useful Improvements in Track-Brakes; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to railway-brakes, but more particularly to an emergency track-brake which is designed to be used in connection with the ordinary air-brakes now in universal use; and my invention is in the nature of an auxiliary brake to be used only in emergencies whereby an additional brake is provided in order to bring the train to a sudden and full stop in a manner which cannot be accomplished by the ordinary air-brakes acting on the wheels of the train as are now in common use. Consequently my brake is only to be applied, when from any cause, such as the bursting of the train-pipe, or where there is reason to bring the train to a sudden and quick stop.

With these objects in view my invention consists in the novel construction of my track-brake and in the combination of the same with the ordinary train-pipe.

My invention also consists in certain novel features of construction and in combinations of parts, which will be first fully described and afterward specifically pointed out in the appended claims.

Referring to the accompanying drawings, Figure 1 is an elevation illustrating the track-brake, showing the brakes in an emergency position. Fig. 2 is a similar view showing the brakes in a released position; and Fig. 3 is a sectional view showing the valve I employ for operating the brake, the said valve being shown in Fig. 3 in an emergency position.

Like numerals of reference indicate the same

parts throughout the several figures, in which—

1 indicates a series of braces secured to the body of the car.

2 indicates the brake-shoes, which are connected to the said braces 1 by means of a link 3, and the said brake-shoes 2 being also connected to a threaded member 4, pivoted to the shoes at 5, said member 4 entering the sleeves 6 for the purpose of adjusting the brake-shoes to the proper position for engaging the track.

7 indicates a cylinder which carries a piston 8, having a piston-rod 9, said piston-rod being connected to a bracket 10, to which the sleeves 6 are pivoted at 11.

12 indicates the train-pipe, and 13 is an auxiliary air-reservoir located, preferably, as shown, in close proximity to the cylinder 7.

14 indicates the valve, which is connected to the train-pipe 12 by means of the pipe 15 and which is also connected to the auxiliary reservoir 13 by means of the pipe 16. A pipe 17 also connects said valve to the cylinder 7.

Referring now to Fig. 3, which shows the interior arrangement of the valve, it will be seen that a port 18 connects with the pipe 15, leading from the train-pipe. Said port 18 leads to the chamber 19, within which is located the graduating stem 20. 21 indicates a chamber above the said chamber 19 and connected thereto by means of the ports 22. Carried in said chamber 21 is a piston 23, carrying a piston-rod 24. Associated with said piston-rod 24 is a slide-valve 25, having the cavity 26 therein. A port 27 is located in the valve-casing and leads to the atmosphere, the slide-valve being provided with a spring 28, which bears against the bushing 29 for holding the said slide-valve snugly in position.

29 indicates the port which is connected to the pipe 16, leading from the auxiliary reservoir 13, and 30 indicates a port in the bushing 29, which leads to the port 31 and leads to the pipe 17, which connects the valve with the cylinder 7. In the side of the chamber 21, near the top thereof, is a feed-groove 32,

and in the top of the piston 23 is a feed-groove 33.

Having thus described the several parts of my invention, its operation is as follows: For all ordinary purposes the usual air-brakes acting on the wheels of the train are sufficient, and the emergency track-brake should not be used only, as before stated, when it is necessary to bring the train to a sudden and quick stop. Should, therefore, for any reason—as, for instance, the bursting of the train-pipe or any causes of emergency—it be desired to bring the train to a full quick stop, the same is accomplished as follows: The auxiliary reservoir 13 is supplied with air under pressure from the train-pipe 12. When there is pressure in the train-pipe 12, said pressure enters the valve 14 through the pipe 15 and into the port 18 in said valve, said pressure entering the chamber 19 and acts against the under side of the piston 23, raising the said piston into the position shown in the dotted line in Fig. 3. The piston therefore being in its raised position, pressure in the chamber 19 passes into the chamber 21 through the feed-groove 32 in the side thereof and through the feed-groove 33 in the top of the piston, the said pressure passing upward out of the port 29 through the pipe 16 and into the auxiliary reservoir 13. When the piston has remained in this position sufficiently long, which would not be more than sixty seconds, the pressure in the auxiliary reservoir 13 and the pressure in the train-pipe and in the chamber 19 become equalized and the piston remains in a raised position, the cavity 26 in the valve 25 bringing into connection the port 30, leading from the cylinder 7, and the port 27, leading to the atmosphere, as shown in dotted lines. This relieves all pressure from the cylinder 7, and the spring 7', which is within the cylinder 7 and under the piston 8, is of sufficient strength to raise the piston 8 within the cylinder 7 and to raise the brake-shoes 2 into the released position, as shown in Fig. 2. During ordinary service application of the ordinary air-brakes the piston 8 and track brake-shoes 2 remain in this position; but the piston 23 is forced down into what is termed "servo-ice" position, which movement is just sufficient to carry the edge of the piston 23 below the feed-groove 32 in the side of the chamber 21 in order to prevent the escape of air from the auxiliary reservoir back into the train-pipe; but when from any cause there is a sudden reduction of pressure in the train-pipe 12 and chamber 19 the pressure in the auxiliary reservoir 13 suddenly forces the piston 23 down into position shown in Fig. 3, which is the emergency position. As said piston is pushed down the slide-valve 25 is carried therewith, which opens the port 30 and allows direct communication between the

port 29, leading from the auxiliary reservoir 13, to the port 30, leading to the cylinder 7. The pressure, therefore, suddenly enters cylinder 7 and lowers the piston 8, carrying the brake-shoes 2 down into emergency position. (Shown in Fig. 1.) The brakes remain in this position until the pressure in the train-pipe 12 is restored and overcomes the pressure in the auxiliary reservoir 13. When the pressure in the train-pipe 12 becomes greater than the pressure in the auxiliary reservoir 13, the piston 23 in the valve is again raised in the position shown in dotted lines in Fig. 3 and the auxiliary reservoir 13 is again recharged, as before described. The slide-valve 25 being also raised with the piston 23, again brings the port 30, leading from the cylinder 7, and the port 27, leading to the atmosphere, into communication, which releases the pressure in the cylinder 7 and allows the spring 7' to raise the piston and release the brake-shoes from the track.

Having thus described the several parts of my invention and its operation, I do not wish to be understood as limiting myself to the exact construction as herein set forth, as various slight changes may be made therein which would fall within the limit and scope of my invention, and I consider myself clearly entitled to all such changes and modifications.

What I claim as my invention, and desire to secure by Letters Patent of the United States, is—

1. In a track-brake to be used in connection with the usual train-pipe, the combination with the usual automatic system for wheel-brakes of an auxiliary reservoir, a cylinder and piston, means for connecting said auxiliary reservoir with the train-pipe, means for connecting the said auxiliary reservoir with the said cylinder and means for allowing pressure in the auxiliary reservoir to enter the said cylinder when there is an emergency application of the wheel-brakes, and brake-shoes adapted to engage the track, substantially as described.

2. In an emergency track-brake, the combination with the train-pipe of the usual automatic system for wheel-brakes of a valve connected thereto, an auxiliary reservoir connected to said valve, a cylinder connected to said valve, a piston in said cylinder, brake-shoes connected to said piston and adapted to be operated thereby, means in said valve for establishing communication between the auxiliary reservoir and the said piston operated by an emergency reduction of pressure in the train-pipe, substantially as described and for the purposes set forth.

3. In an emergency-brake, the combination with the train-pipe of the usual automatic system for wheel-brakes of a valve connected thereto, an auxiliary reservoir connected to

said valve and a cylinder and piston connected to said valve, brake-shoes connected to the piston, means for allowing communication between the train-pipe and the said auxiliary reservoir for charging said reservoir and means in said valve for allowing a direct communication between the said auxiliary reservoir and the said cylinder during an emergency application of the wheel-brakes and means in said valve for allowing direct com-

munication between the said cylinder and the atmosphere, substantially as described and for the purposes set forth.

In testimony whereof I affix my signature in presence of two witnesses.

NELS EDWARD KNUTZEN.
